UNITED STATES PATENT OFFICE

134,784

DESIGN FOR A STAMP BUTTON OR SIMILAR ARTICLE

Charles B. Keiser, Wilkes-Barre, Pa.

Application September 4, 1942, Serial No. 108,120

Term of patent 3½ years

To all whom it may concern:

Be it known that I, Charles B. Keiser, a citizen of the United States, residing at Wilkes-Barre, in the county of Luzerne and State of Pennsylvania, have invented a new, original, and ornamental Design for a Stamp Button or Similar Article, of which the following is a specification, reference being had to the accompanying drawing, forming part thereof.

Figure 1 is a front elevational view of a stamp button or similar article showing my new design, and

I claim:

The ornamental design for a stamp button or similar article, substantially as shown.

CHARLES B. KEISER.
